UNITED STATES PATENT OFFICE.

SAMUEL H. FANNING, OF DALLAS, TEXAS, ASSIGNOR TO LIBERTY MAP CABINET COMPANY, A FIRM COMPOSED OF SAMUEL H. FANNING, WILLIAM G. BREG, G. W. WARE, W. H. FLIPPEN, J. W. EVERMAN, L. G. SCOTT, AND A. L. MOON, ALL OF DALLAS, TEXAS.

MAP-CABINET.

1,258,325.

Specification of Letters Patent. Patented Mar. 5, 1918.

Application filed January 12, 1917. Serial No. 142,030.

To all whom it may concern:

Be it known that I, SAMUEL H. FANNING, a citizen of the United States, residing at Dallas, in the county of Dallas and State of Texas, have invented certain new and useful Improvements in Map-Cabinets, of which the following is a specification.

This invention relates to improvements in cabinets for maps, charts, and the like, and has for one of its objects to provide a device of this character whereby a plurality of maps or charts may be rolled upon drums and any desired map or chart displayed.

Another object of the invention is to provide a device whereby maps or charts are protected, while at the same time maintained in position for displaying. With these and other objects in view, the invention consists in certain novel features of construction, as hereinafter shown and described and then specifically pointed out in the claims; and in the drawings illustrative of the preferred embodiment of the invention.

Figure 1 is a front view with the protecting apron partially raised.

Fig. 2 is a vertical section on the line 2—2 of Fig. 1.

Fig. 3 is a rear elevation with the back removed.

Fig. 4 is an enlarged perspective view of a portion of one of the idler carrier rollers illustrating the manner of constructing the tension device.

Fig. 5 is a detached perspective view of one of the pinion carrying studs of the winding drums.

Fig. 6 is an enlarged sectional detail illustrating the manner of constructing the winding drum operating mechanism.

Fig. 7 represents enlarged perspective views of the supports for the winding drum operating mechanism with the parts separated.

Fig. 8 is a side elevation of one of the winding drum operating gears.

Fig. 9 is a detached perspective view of one of the drum guard supporting brackets.

Corresponding and like parts are referred to in the following description and indicated in all the views of the drawings by the same reference characters.

The improved device may be supported upon a suitable base or stand, or attached to a wall as may be required, but for the pur-

pose of illustration is shown supported upon a suitable stand or frame represented as a whole at 10. The improved device comprises a frame or casing including end members 11—12, a top 13, a bottom 14, and detachable back comprising upper member 15, lower member 16, and an intermediate member 17, the member 17 being spaced from the confronting edges of the terminal members 15—16. The members 15—16—17 are secured to the casing members, preferably by screws, and are designed to be removed only when the operating mechanism is installed or needs repairing.

The vacant space between the members 15—17 is occupied by a filler member 18, while the space between members 16—17 is occupied by detachable filler member 19. The members 18—19 are disposed opposite the map or chart receiving drums, to render the drums and their operating mechanism accessible for changing the maps or charts or adding thereto when required.

The end members 11—12 are provided with guide channels or runways 20 to receive the ends of the slats 21 of a slatted apron, the slats being glued or otherwise attached to a canvas or other fabric backing 22.

The terminal slats of the apron are larger than the remaining slats and are reduced at their ends to enable them to travel without cramping over the upwardly curved portion 23 of the guideway. The lower terminal slat of the apron is provided with suitable hand grip devices 24, whereby the apron may be actuated.

It will be obvious by this arrangement that the front of the cabinet may be closed by drawing the apron downwardly and may be opened by moving the apron upwardly, the slats traveling within the guideway.

Attached to the inner faces of the end members 11—12 near their upper and lower ends are plates 24 each having a central bearing. The plates 24 are located near the forward edges of the end members 11—12. The bearings of the upper pair of plates receive studs 25 which support an upper guide roller 26, while the bearings in the lower plates receive studs 27 which support a lower guide roller 28. The forward faces of the rollers 26—28 are located slightly in the rear of the apron device, as shown in Fig. 2. Bearing against each end of the

guide roller 26 and mounted loosely upon the studs 25 are guard washers 29, while similar washers 30 bear against the ends of the guide roller 28 and are loosely mounted 5 upon the studs 27. A spring 31 is located between each of the washers 29 and the adjacent plate 24, while similar springs 32 are located between washers 30 and the adjacent plates 24, the springs operating as tension 10 devices to prevent the guide rollers from being rotated too easily.

Located beneath the upper plates 24 is a transverse supporting member 33, while a similar supporting member 34 is located 15 above the lower plates 24. Extending between the terminal members 11-12 are a plurality of transverse holding members 35, spaced at uniform distances and arranged in vertical alinement with the plates 33-34. 20 The members 33-34-35 serve as supports for a plurality of slats 36 spaced at uniform distances. The slats serve as a background or surface over which the maps and charts are moved, and prevent the latter from being deflected intermediate the guide rollers. 25 The end slats or those next to the ends 11-12 of the casing, are relatively wide as shown in Fig. 3, and serve as guards between the yieldable disks of the winding drums and the fabric belt, as hereafter explained.

Attached to the inner face of the end member 12 intermediate the plates 24 which are attached to the member 12, are outer plates 37. The plates 37 are located adjacent to the guide rollers 26 and 28, as shown in Fig. 3.

Spaced from each of the outer plates 37 is an inner plate 38, the plates 37-38 being maintained in spaced relation by spacer 40 blocks 39. The blocks 39 are provided with dowel pins 40 which extend through suitable apertures in the outer plates 38. The plates 37-38 and the spacer members 39 are perforated to receive holding screws 41 by 45 which the plates and their spacer members are attached to the end member 12 of the casing. The dowel pins operate to maintain the spacer members in position and prevent them from rotating upon the screws.

50 Located between the plates 37-38 is a relatively large gear 42, the gear having a relatively large hub 44 which extends from opposite sides thereof and engages in bearings in the plates 37-38. The bore of the hub 44 is square or otherwise than round to receive the correspondingly formed terminal 45 of a crank 46 which is extended through a suitable aperture in the end member 12. By this means the gear may be rotated from 55 the exterior of the casing. The material which surrounds the crank aperture in the member 12 is protected by a metal sleeve 47.

Two sets of the plates 37-38 together with the gear 42 are employed and located 60 in vertical alinement and in spaced relation,

as shown in Fig. 2, and as the plates and their connections are precisely alike the description of one will suffice for both.

A pinion 48 is located between each pair of the plates 37-38 and engages with the 70 gears 42. Each of the pinions 48 is mounted for rotation upon a stud 49, the latter engaging in suitable bearings in the plates. By this means it will be obvious that when the crank 46 is applied to the hub 44 of the 75 gear 42 and rotated, motion will be transmitted at increased speed to the stud 49.

Attached to the end member 11 are plates 50 similar to the plates 37 but shorter and secured in place by screws or like devices. 80 Each of the plates 50 is provided with a bearing to receive a stud 52 similar to the studs 49. The studs are designed to support winding drums 53, the drums being preferably wood and the studs pointed and the 85 points formed square or otherwise than round so that when driven into the drums they will be prevented from rotation therein. Bearing against the ends of the drums 53 are relatively large disks 54, each disk being loosely mounted upon the studs 49-52. Disposed between the disks 54 and the plates 38 and 50 are tension springs 54' which serve as brakes or tension devices to the drums to prevent them from rotating 90 too easily. Attached to the drums 53 is a fabric sheet or belt 55, the latter being passed over the guide rollers 26-28 and extending forwardly of the guard slats 36. The maps or charts are attached to the fabric 100 member 55 in any suitable manner.

A defining frame 60 is disposed between the apron 21-22 and the map and chart supporting belt 55 in the rear of which the belt operates. The frame 60 not only defines the exposed portions of the maps or charts and forms a frame thereto, but likewise cooperates with the slats 36 to guide the belt and prevent outward displacement.

By this arrangement it will be obvious 110 that when the crank 46 is applied to the hub of the upper gear 42 and rotated in one direction the fabric member 55 together with the maps or charts carried thereby will be wound upon the upper drum 53 and 115 unwound from the lower drum. Then if the crank be transferred to the hub of the lower gear and rotated, the fabric member together with its maps or charts will be wound upon the lower drum and unwound 120 from the upper drum. By this means any desired map or chart which may be located upon the fabric member will be exposed when the curtain device is elevated. The tension spring devices operate to hold the 125 guard rollers and the drums with sufficient force to prevent the fabric member 55 and its attached maps or charts from working loose, but will retain the exposed map or chart in strained condition.

Extending between the end members 11-12 below the line of the upper drum 53 are a plurality of guard slats 56, while a similar series of slats 57 extend between the 5 end members 11-12 and below the lower line of the lower drum 53. The slats are arranged in curved position and serve as guards to the fabric member 55 and its attached 10 maps or charts when fully wound upon the drums to prevent them from sagging down in event of the tension devices not being of sufficient strength. The slats 56 are supported at their ends by curved cleat devices 58, while the slats 57 are supported by similar 15 curved cleats 59. The detachable rear member 18 is located opposite the upper drum and its operating mechanism, while the lower detachable member 19 is located opposite the lower drum and its operating 20 mechanism, so that the drums and their operating mechanism are readily accessible to enable the maps or charts to be renewed or changed.

The maps or charts may thus be renewed 25 or changed by simply removing one or both the members 18-19.

The confronting edges of the stationary back members 15-16 and 17 and the removable back members 18 and 19 are rabbed, as shown in Fig. 2, to assist in holding 30 them in position.

Having thus described the invention, what is claimed as new is—

1. An apparatus of the class described

comprising a casing including end members 35 and open at the front, guide rollers mounted for rotation in said end members near the upper and lower portions of the casing, coacting winding drums mounted for rotation between said end members and having 40 guard disks at the ends, a flexible element connected to said drums and leading over said guide rollers and adapted to contact with said disks, upper and lower transverse supports extending between said end members and between said rollers, and guard members connected respectively to said transverse supports and directed between said flexible element and said movable guard disks and preventing contact of the 45 flexible element therewith.

2. An apparatus of the class described, comprising a casing including end members and open at the front, guide rollers mounted for rotation in said end members near 55 the upper and lower portions of the casing, coacting winding drums mounted for rotation between said end members, guard disks at the ends of the rollers and drums and rotative independently of the same, yieldable 60 tension devices bearing against said disks, and a flexible element connected to said drums and leading over said guide rollers and adapted to contact with said yieldable disks and prevented thereby from displacement.

In testimony whereof I affix my signature.
SAMUEL H. FANNING. [L.S.]
